UNITED STATES PATENT OFFICE.

JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.

BUTTON-ATTACHING MACHINE.

1,089,649.

Specification of Letters Patent. Patented Mar. 10, 1914.

Application filed December 1, 1911. Serial No. 663,343.

To all whom it may concern:

Be it known that I, JOHN KIEWICZ, a citizen of the United States, residing at Hyde Park, in the county of Norfolk and State of Massachusetts, have invented certain new and useful Improvements in Button-Attaching Machines, of which the following is a specification, reference being had therein to the accompanying drawing.

10 My invention relates to button sewing machines and more particularly to that type of button sewing machine wherein a plurality of shank-eyed buttons (such as shoe buttons) are sewed successively and at 15 spaced apart points upon any given article (such as a shoe); a prior example of that type of machine which may be referred to for convenience, being that illustrated in U. S. Patent No. 886,826, patented May 5, 20 1908.

Among the objects of the present improvements are the production of a novel, simple and direct acting machine, one which may operate at high speed, and will possess 25 great durability and ease and quietness of operation.

Other objects are to provide a special and advantageous means of actuating the cast-off bar which coöperates with the needle, 30 and to secure a certain coöperation with the needle; also to provide a means or device for backing up or affording a support to the sewing needle while the thread is under tension, as for example when the loop is 35 being spread preparatory to passing it over the button.

Further objects and advantages in the present improvements will be described or will be understood in the following specification.

40 For convenience I have shown the present improvements as applied to the type of machine illustrated in prior Patent No. 886,826 before referred to, in which type of machine a primary thread loop is first formed and drawn through the eye of the button, followed by the formation of a secondary loop drawn through the fabric adjacent to the first loop and then interlocked 45 with the first loop by being drawn through it, and thereafter spread over the head of the button; the work being automatically fed between the formation of the first and second loop and between the attachment of 50 two successive buttons by a work feeding

mechanism fully shown and described in said prior patent and not *per se* forming any part of the present improvements.

I will first describe an embodiment of the present improvements and will thereafter point out the novel features in the claims.

In the accompanying drawings forming a part hereof, Figure 1 is a front elevation partly in section of a button sewing machine embodying my present improvements. Fig. 2 is a left end elevation of the mechanism shown in Fig. 1. Figs. 3 and 4 are partial left end views, showing certain parts of the sewing mechanism in two successive positions. Figs. 5 and 6 are partial top views, showing the needle backing device and its operating cam in two successive positions, and showing the needle bar and spreader bar in cross-section. Fig. 7 is a right-hand view of the upper ends of the cast-off bar and needle bar, together with the arm which actuates the cast-off bar, showing the connection between the arm and the bar. Fig. 8 is a partial top view showing the loop spreader and spreader bar. Fig. 9 is a diagram showing the preferred timing of the two cams which respectively actuate the needle bar and the cast-off bar. Fig. 10 is a top view of the mechanism shown in Figs. 1 and 2.

85

Similar letters of reference designate corresponding parts in the several figures of the drawings.

I will first describe some of the general machine parts which are not new herein but are well known in this type of machine. Thus the base A supports a head A' shown as a hollow casting containing cams, etc., the upper portion of said head being formed into a horizontally extending arm A² which over- 90 hangs the sewing position.

95 It should be explained that the work X, which may be a piece of leather, is supposed to be fed from the operator of a machine, that is toward the left in Figs. 2, 3 and 4, 100 while the buttons x are sewed thereto by means of the thread y drawn from the usual spool or supply. A work support B mounted in a standard B' may be yieldingly or otherwise upheld so that the work 105 may be pressed between the support B and the presser foot C opposed thereto; and any desired means may be employed for causing the separation of the work support and presser foot at the times that the work has 110

to be fed during the process of attaching a row of buttons.

A main shaft Z may be of ordinary arrangement and operation, and will have secured upon it substantially all of the operating cams of the machine. At the right hand of the main shaft Z will be seen a pulley z, either loose or fast on the shaft, adapted to be continuously driven when desired by a power belt; also a hand wheel z' to facilitate manual operation of the main shaft, as will be well understood. Any ordinary clutch mechanism may be employed between pulley z and shaft Z, whereby the shaft may be disconnected at will to render the machine idle.

In the machine to which the present improvements are shown as applied, the needle D is of the type having a hook instead of an eye, it passing downwardly through the work from above to the point where the thread mechanism is located, and said hook serving to draw a loop up through the work and through the eye of the button, or through a previous loop as the case may be. The needle D is shown secured at the lower end of a needle bar D' which is fitted to slide vertically in the arm A², and said needle may be reciprocated in any desired manner, as for example through bell crank d', Fig. 1, link d² and arm d³, the latter having a pin which engages in the cam slot of a cam d⁴ mounted on the main shaft Z. It will be understood that the presser foot C is apertured or slotted at c which permits the passage of the needle therethrough, and also permits the line of attached buttons to pass along with the feeding of the work.

For feeding along the work any convenient means may be employed, such for example as the feed prong shown in Patent 886,826 before mentioned; but as the work feeding mechanism *per se* forms no part of the present invention, the mechanism thereof is omitted herefrom. It will be understood, however, that the feed prong serves to feed the work at one period a distance substantially equal to the space between two buttons, and at another period the comparatively slight distance between the two punctures through which the loops extend for attaching a given button.

Any desired construction of thread handling mechanism may be employed, and as that mechanism forms no part *per se* of the present invention, it is not completely shown; although a looper bar F is indicated carrying a looper f at its upper end, the looper carrying the thread and being adapted to swing at proper times to carry the thread into the hook of the needle. The swinging of the looper bar and looper may be effected by mechanism not shown, actuated by one of the cams on the main shaft Z.

65 A loop spreader G is mounted and actu-

ated to coöperate with the other parts. The details of its fittings and actuating means will be hereinafter described. Button feeding mechanism will be understood, and it will be of a nature to feed buttons one at a time into proper relation to the needle for the attachment successively of the buttons at spaced apart points on the work. For clearness the button feeding mechanism is entirely omitted.

75 The contour and therefore the timing of all of the cams herein shown and described, will be such as to cause the different instrumentalities to harmoniously coöperate for forming the thread loops and locking them 80 with the buttons into attaching knots.

The mechanisms so far as above described are all known in the art and no claim of novelty to them *per se* is made herein.

I will now describe the novel constructions 85 and arrangements involved in the present improvements, and will then explain their coöperation with the other parts of the machine. A cast-off employed in connection with a hooked needle in a machine of the type referred to, has several functions to perform. The cast-off must move at times in conjunction with the needle, and at other times it must have movements relatively to the needle. The cast-off must at times hold 95 the loop of thread in engagement with the needle's hook, and at other times it must effect the release of the loop. In attaching buttons by a knot similar to that illustrated and described herein, the cast-off also has 100 the function of holding open and away from the needle the first loop or bight of thread, while the second loop is pulled through the first loop. In performing this function generally, the cast-off is caused to descend into 105 contact with the work, or even to partially enter the puncture formed by the needle.

It has been usual to arrange the needle bar and cast-off bar in close proximity to each other, and heretofore the operation of 110 the cast-off has been effected by connections formed between the two bars, these connections usually taking the form of projections engaging other projections or recesses, so that in their operation the two bars are 115 intimately associated, and only the needle bar has been actuated from the driving mechanism, the other taking its movements from the needle bar. With that type of mechanism there of necessity will occur sudden 120, 125, 130, 135, 140, 145, 150, 155, 160, 165, 170, 175, 180, 185, 190, 195, 200, 205, 210, 215, 220, 225, 230, 235, 240, 245, 250, 255, 260, 265, 270, 275, 280, 285, 290, 295, 300, 305, 310, 315, 320, 325, 330, 335, 340, 345, 350, 355, 360, 365, 370, 375, 380, 385, 390, 395, 400, 405, 410, 415, 420, 425, 430, 435, 440, 445, 450, 455, 460, 465, 470, 475, 480, 485, 490, 495, 500, 505, 510, 515, 520, 525, 530, 535, 540, 545, 550, 555, 560, 565, 570, 575, 580, 585, 590, 595, 600, 605, 610, 615, 620, 625, 630, 635, 640, 645, 650, 655, 660, 665, 670, 675, 680, 685, 690, 695, 700, 705, 710, 715, 720, 725, 730, 735, 740, 745, 750, 755, 760, 765, 770, 775, 780, 785, 790, 795, 800, 805, 810, 815, 820, 825, 830, 835, 840, 845, 850, 855, 860, 865, 870, 875, 880, 885, 890, 895, 900, 905, 910, 915, 920, 925, 930, 935, 940, 945, 950, 955, 960, 965, 970, 975, 980, 985, 990, 995, 1000, 1005, 1010, 1015, 1020, 1025, 1030, 1035, 1040, 1045, 1050, 1055, 1060, 1065, 1070, 1075, 1080, 1085, 1090, 1095, 1100, 1105, 1110, 1115, 1120, 1125, 1130, 1135, 1140, 1145, 1150, 1155, 1160, 1165, 1170, 1175, 1180, 1185, 1190, 1195, 1200, 1205, 1210, 1215, 1220, 1225, 1230, 1235, 1240, 1245, 1250, 1255, 1260, 1265, 1270, 1275, 1280, 1285, 1290, 1295, 1300, 1305, 1310, 1315, 1320, 1325, 1330, 1335, 1340, 1345, 1350, 1355, 1360, 1365, 1370, 1375, 1380, 1385, 1390, 1395, 1400, 1405, 1410, 1415, 1420, 1425, 1430, 1435, 1440, 1445, 1450, 1455, 1460, 1465, 1470, 1475, 1480, 1485, 1490, 1495, 1500, 1505, 1510, 1515, 1520, 1525, 1530, 1535, 1540, 1545, 1550, 1555, 1560, 1565, 1570, 1575, 1580, 1585, 1590, 1595, 1600, 1605, 1610, 1615, 1620, 1625, 1630, 1635, 1640, 1645, 1650, 1655, 1660, 1665, 1670, 1675, 1680, 1685, 1690, 1695, 1700, 1705, 1710, 1715, 1720, 1725, 1730, 1735, 1740, 1745, 1750, 1755, 1760, 1765, 1770, 1775, 1780, 1785, 1790, 1795, 1800, 1805, 1810, 1815, 1820, 1825, 1830, 1835, 1840, 1845, 1850, 1855, 1860, 1865, 1870, 1875, 1880, 1885, 1890, 1895, 1900, 1905, 1910, 1915, 1920, 1925, 1930, 1935, 1940, 1945, 1950, 1955, 1960, 1965, 1970, 1975, 1980, 1985, 1990, 1995, 2000, 2005, 2010, 2015, 2020, 2025, 2030, 2035, 2040, 2045, 2050, 2055, 2060, 2065, 2070, 2075, 2080, 2085, 2090, 2095, 2100, 2105, 2110, 2115, 2120, 2125, 2130, 2135, 2140, 2145, 2150, 2155, 2160, 2165, 2170, 2175, 2180, 2185, 2190, 2195, 2200, 2205, 2210, 2215, 2220, 2225, 2230, 2235, 2240, 2245, 2250, 2255, 2260, 2265, 2270, 2275, 2280, 2285, 2290, 2295, 2300, 2305, 2310, 2315, 2320, 2325, 2330, 2335, 2340, 2345, 2350, 2355, 2360, 2365, 2370, 2375, 2380, 2385, 2390, 2395, 2400, 2405, 2410, 2415, 2420, 2425, 2430, 2435, 2440, 2445, 2450, 2455, 2460, 2465, 2470, 2475, 2480, 2485, 2490, 2495, 2500, 2505, 2510, 2515, 2520, 2525, 2530, 2535, 2540, 2545, 2550, 2555, 2560, 2565, 2570, 2575, 2580, 2585, 2590, 2595, 2600, 2605, 2610, 2615, 2620, 2625, 2630, 2635, 2640, 2645, 2650, 2655, 2660, 2665, 2670, 2675, 2680, 2685, 2690, 2695, 2700, 2705, 2710, 2715, 2720, 2725, 2730, 2735, 2740, 2745, 2750, 2755, 2760, 2765, 2770, 2775, 2780, 2785, 2790, 2795, 2800, 2805, 2810, 2815, 2820, 2825, 2830, 2835, 2840, 2845, 2850, 2855, 2860, 2865, 2870, 2875, 2880, 2885, 2890, 2895, 2900, 2905, 2910, 2915, 2920, 2925, 2930, 2935, 2940, 2945, 2950, 2955, 2960, 2965, 2970, 2975, 2980, 2985, 2990, 2995, 3000, 3005, 3010, 3015, 3020, 3025, 3030, 3035, 3040, 3045, 3050, 3055, 3060, 3065, 3070, 3075, 3080, 3085, 3090, 3095, 3100, 3105, 3110, 3115, 3120, 3125, 3130, 3135, 3140, 3145, 3150, 3155, 3160, 3165, 3170, 3175, 3180, 3185, 3190, 3195, 3200, 3205, 3210, 3215, 3220, 3225, 3230, 3235, 3240, 3245, 3250, 3255, 3260, 3265, 3270, 3275, 3280, 3285, 3290, 3295, 3300, 3305, 3310, 3315, 3320, 3325, 3330, 3335, 3340, 3345, 3350, 3355, 3360, 3365, 3370, 3375, 3380, 3385, 3390, 3395, 3400, 3405, 3410, 3415, 3420, 3425, 3430, 3435, 3440, 3445, 3450, 3455, 3460, 3465, 3470, 3475, 3480, 3485, 3490, 3495, 3500, 3505, 3510, 3515, 3520, 3525, 3530, 3535, 3540, 3545, 3550, 3555, 3560, 3565, 3570, 3575, 3580, 3585, 3590, 3595, 3600, 3605, 3610, 3615, 3620, 3625, 3630, 3635, 3640, 3645, 3650, 3655, 3660, 3665, 3670, 3675, 3680, 3685, 3690, 3695, 3700, 3705, 3710, 3715, 3720, 3725, 3730, 3735, 3740, 3745, 3750, 3755, 3760, 3765, 3770, 3775, 3780, 3785, 3790, 3795, 3800, 3805, 3810, 3815, 3820, 3825, 3830, 3835, 3840, 3845, 3850, 3855, 3860, 3865, 3870, 3875, 3880, 3885, 3890, 3895, 3900, 3905, 3910, 3915, 3920, 3925, 3930, 3935, 3940, 3945, 3950, 3955, 3960, 3965, 3970, 3975, 3980, 3985, 3990, 3995, 4000, 4005, 4010, 4015, 4020, 4025, 4030, 4035, 4040, 4045, 4050, 4055, 4060, 4065, 4070, 4075, 4080, 4085, 4090, 4095, 4100, 4105, 4110, 4115, 4120, 4125, 4130, 4135, 4140, 4145, 4150, 4155, 4160, 4165, 4170, 4175, 4180, 4185, 4190, 4195, 4200, 4205, 4210, 4215, 4220, 4225, 4230, 4235, 4240, 4245, 4250, 4255, 4260, 4265, 4270, 4275, 4280, 4285, 4290, 4295, 4300, 4305, 4310, 4315, 4320, 4325, 4330, 4335, 4340, 4345, 4350, 4355, 4360, 4365, 4370, 4375, 4380, 4385, 4390, 4395, 4400, 4405, 4410, 4415, 4420, 4425, 4430, 4435, 4440, 4445, 4450, 4455, 4460, 4465, 4470, 4475, 4480, 4485, 4490, 4495, 4500, 4505, 4510, 4515, 4520, 4525, 4530, 4535, 4540, 4545, 4550, 4555, 4560, 4565, 4570, 4575, 4580, 4585, 4590, 4595, 4600, 4605, 4610, 4615, 4620, 4625, 4630, 4635, 4640, 4645, 4650, 4655, 4660, 4665, 4670, 4675, 4680, 4685, 4690, 4695, 4700, 4705, 4710, 4715, 4720, 4725, 4730, 4735, 4740, 4745, 4750, 4755, 4760, 4765, 4770, 4775, 4780, 4785, 4790, 4795, 4800, 4805, 4810, 4815, 4820, 4825, 4830, 4835, 4840, 4845, 4850, 4855, 4860, 4865, 4870, 4875, 4880, 4885, 4890, 4895, 4900, 4905, 4910, 4915, 4920, 4925, 4930, 4935, 4940, 4945, 4950, 4955, 4960, 4965, 4970, 4975, 4980, 4985, 4990, 4995, 5000, 5005, 5010, 5015, 5020, 5025, 5030, 5035, 5040, 5045, 5050, 5055, 5060, 5065, 5070, 5075, 5080, 5085, 5090, 5095, 5100, 5105, 5110, 5115, 5120, 5125, 5130, 5135, 5140, 5145, 5150, 5155, 5160, 5165, 5170, 5175, 5180, 5185, 5190, 5195, 5200, 5205, 5210, 5215, 5220, 5225, 5230, 5235, 5240, 5245, 5250, 5255, 5260, 5265, 5270, 5275, 5280, 5285, 5290, 5295, 5300, 5305, 5310, 5315, 5320, 5325, 5330, 5335, 5340, 5345, 5350, 5355, 5360, 5365, 5370, 5375, 5380, 5385, 5390, 5395, 5400, 5405, 5410, 5415, 5420, 5425, 5430, 5435, 5440, 5445, 5450, 5455, 5460, 5465, 5470, 5475, 5480, 5485, 5490, 5495, 5500, 5505, 5510, 5515, 5520, 5525, 5530, 5535, 5540, 5545, 5550, 5555, 5560, 5565, 5570, 5575, 5580, 5585, 5590, 5595, 5600, 5605, 5610, 5615, 5620, 5625, 5630, 5635, 5640, 5645, 5650, 5655, 5660, 5665, 5670, 5675, 5680, 5685, 5690, 5695, 5700, 5705, 5710, 5715, 5720, 5725, 5730, 5735, 5740, 5745, 5750, 5755, 5760, 5765, 5770, 5775, 5780, 5785, 5790, 5795, 5800, 5805, 5810, 5815, 5820, 5825, 5830, 5835, 5840, 5845, 5850, 5855, 5860, 5865, 5870, 5875, 5880, 5885, 5890, 5895, 5900, 5905, 5910, 5915, 5920, 5925, 5930, 5935, 5940, 5945, 5950, 5955, 5960, 5965, 5970, 5975, 5980, 5985, 5990, 5995, 6000, 6005, 6010, 6015, 6020, 6025, 6030, 6035, 6040, 6045, 6050, 6055, 6060, 6065, 6070, 6075, 6080, 6085, 6090, 6095, 6100, 6105, 6110, 6115, 6120, 6125, 6130, 6135, 6140, 6145, 6150, 6155, 6160, 6165, 6170, 6175, 6180, 6185, 6190, 6195, 6200, 6205, 6210, 6215, 6220, 6225, 6230, 6235, 6240, 6245, 6250, 6255, 6260, 6265, 6270, 6275, 6280, 6285, 6290, 6295, 6300, 6305, 6310, 6315, 6320, 6325, 6330, 6335, 6340, 6345, 6350, 6355, 6360, 6365, 6370, 6375, 6380, 6385, 6390, 6395, 6400, 6405, 6410, 6415, 6420, 6425, 6430, 6435, 6440, 6445, 6450, 6455, 6460, 6465, 6470, 6475, 6480, 6485, 6490, 6495, 6500, 6505, 6510, 6515, 6520, 6525, 6530, 6535, 6540, 6545, 6550, 6555, 6560, 6565, 6570, 6575, 6580, 6585, 6590, 6595, 6600, 6605, 6610, 6615, 6620, 6625, 6630, 6635, 6640, 6645, 6650, 6655, 6660, 6665, 6670, 6675, 6680, 6685, 6690, 6695, 6700, 6705, 6710, 6715, 6720, 6725, 6730, 6735, 6740, 6745, 6750, 6755, 6760, 6765, 6770, 6775, 6780, 6785, 6790, 6795, 6800, 6805, 6810, 6815, 6820, 6825, 6830, 6835, 6840, 6845, 6850, 6855, 6860, 6865, 6870, 6875, 6880, 6885, 6890, 6895, 6900, 6905, 6910, 6915, 6920, 6925, 6930, 6935, 6940, 6945, 6950, 6955, 6960, 6965, 6970, 6975, 6980, 6985, 6990, 6995, 7000, 7005, 7010, 7015, 7020, 7025, 7030, 7035, 7040, 7045, 7050, 7055, 7060, 7065, 7070, 7075, 7080, 7085, 7090, 7095, 7100, 7105, 7110, 7115, 7120, 7125, 7130, 7135, 7140, 7145, 7150, 7155, 7160, 7165, 7170, 7175, 7180, 7185, 7190, 7195, 7200, 7205, 7210, 7215, 7220, 7225, 7230, 7235, 7240, 7245, 7250, 7255, 7260, 7265, 7270, 7275, 7280, 7285, 7290, 7295, 7300, 7305, 7310, 7315, 7320, 7325, 7330, 7335, 7340, 7345, 7350, 7355, 7360, 7365, 7370, 7375, 7380, 7385, 7390, 7395, 7400, 7405, 7410, 7415, 7420, 7425, 7430, 7435, 7440, 7445, 7450, 7455, 7460, 7465, 7470, 7475, 7480, 7485, 7490, 7495, 7500, 7505, 7510, 7515, 7520, 7525, 7530, 7535, 7540, 7545, 7550, 7555, 7560, 7565, 7570, 7575, 7580, 7585, 7590, 7595, 7600, 7605, 7610, 7615, 7620, 7625, 7630, 7635, 7640, 7645, 7650, 7655, 7660, 7665, 7670, 7675, 7680, 7685, 7690, 7695, 7700, 7705, 7710, 7715, 7720, 7725, 7730, 7735, 7740, 7745, 7750, 7755, 7760, 7765, 7770, 7775, 7780, 7785, 7790, 7795, 7800, 7805, 7810, 7815, 7820, 7825, 7830, 7835, 7840, 7845, 7850, 7855, 7860, 7865, 7870, 7875, 7880, 7885, 7890, 7895, 7900, 7905, 7910, 7915, 7920, 7925, 7930, 7935, 7940, 7945, 7950, 7955, 7960, 7965, 7970, 7975, 7980, 7985, 7990, 7995, 8000, 8005, 8010, 8015, 8020, 8025, 8030, 8035, 8040, 8045, 8050, 8055, 8060, 8065, 8070, 8075, 8080, 8085, 8090, 8095, 8100, 8105, 8110, 8115, 8120, 8125, 8130, 8135, 8140, 8145, 8150, 8155, 8160, 8165, 8170, 8175, 8180, 8185, 8190, 8195, 8200, 8205, 8210, 8215, 8220, 8225, 8230, 8235, 8240, 8245, 8250, 8255, 8260, 8265, 8270, 8275, 8280, 8285, 8290, 8295, 8300, 8305, 8310, 8315, 8320, 8325, 8330, 8335, 8340, 8345, 8350, 8355, 8360, 8365, 8370, 8375, 8380, 8385, 8390, 8395, 8400, 8405, 8410, 8415, 8420, 8425, 8430, 8435, 8440, 8445, 8450, 8455, 8460, 8465, 8470, 8475, 8480, 8485, 8490, 8495, 8

ther that the cast-off bar was capable of no movement except such as was imparted to it by the needle bar. Moreover with such mechanism smooth running of the parts was impossible, and especially the descent of the cast-off into contact with the fabric could not be made to take place in a positive yet easy manner such as would be desirable to prevent injury to the fabric and to the mechanism. Further the designer of the machine was restricted both as to the manner in which the needle might be operated, and also in the cast-off movements; and the old type of mechanism was subject to wear and 15 breakage besides causing excessive vibration and noise such as to constitute a positive detriment.

An object of the mechanism about to be described is to overcome the above objections, and in a broad sense such mechanism for overcoming those objections may be stated to contemplate the combination with the hooked needle and the cast-off located to coöperate therewith, of one cam for effecting the needle movements and another cam for effecting the cast-off movements. It will be understood that each of the members is controlled in its movements solely by its own cam. By this arrangement the 39 timing of the cast-off relatively to the needle movements can be calculated and effected in any preferred manner. Indeed the timing of both the needle and the cast-off may thereby be rendered whatever the judgment 35 of the designer dictates. It will be understood that while separate cams are employed for the two members, both cams are actuated from the same main or power shaft, and indeed the respective cam surfaces might 40 be formed upon either one or two shaft operated members so long as the arrangement permits the movements of the respective members to be independently determined.

The needle D, its operating cam d^4 and 45 the intermediate connections have already been described. The details of the cam d^4 and the timing thereof have not been described but will hereinafter be described in connection with a diagrammatical representation thereof.

The cast-off H may itself be of any preferred form, for example as shown, it being located and fitted to coöperate with the hook of the needle D, and said cast-off being preferably secured to a reciprocating cast-off bar H' which may be arranged in a similar location to that heretofore known. The cast-off bar is actuated through a clamp or member h', clamped to its upper end, and for convenience said member h' may be apertured to engage or surround the needle bar D' in a loose manner, merely for the purposes of guidance and not to afford any operative connection between the two bars.

65 The clamp h' has formed on its right-

hand side Fig. 1, a short groove constituted by a pair of projections h^2 horizontal and parallel to each other. These are to receive between them a roller h^3 , as plainly seen in Fig. 7, said roller being attached at the forward end of an oscillating arm h^4 whose rear end is fast on the horizontal shaft h^5 which actuates it. Said shaft h^5 has its left end journaled in a projection h^6 from the overhanging arm A², and its right-hand end 70 in a standard h^7 at the other end of the machine. It is clear that oscillation of shaft h^5 will effect the swinging of arm h^4 and thereby upward and downward movements of the cast-off bar and cast-off.

A cam is proposed to be employed for causing the actuation of the parts just described, although in using the term cam in this connection I intend to include any equivalents therefor. The cam may operate 85 through a groove thus bearing on both sides of its follower, or it may have only a single cam surface, in which latter case a spring should be employed to keep the follower in contact with the cam. Such a spring h^8 is 90 shown, it being for convenience in the form of a helix under tension, attached at one end to a sleeve h^9 on shaft h^6 , and at the other end to standard h^7 . The tendency of the spring h^8 is to rotate the shaft h^6 in a 95 right-hand direction, Figs. 2, 3 and 4, and thereby lower the cast-off bar.

For opposing the spring h^8 and raising the cast-off bar in the proper manner and at the proper times, a cam J may be employed, 100 located at any convenient point in the machine, for example directly upon the main shaft Z. The contour of the cam J is shown in Figs. 2, 3 and 4, each of which indicates it in a different position. Bearing upon the 105 cam J is a roller j mounted upon an arm j', pivoted at j² to a fixed part of the machine, and said arm j' has pivoted to it at the point j³ a link j⁴ extending upwardly to an arm j⁵ secured to the horizontal shaft h^6 already 110 referred to. By the connection described the cam J when an eccentric portion comes into action, either raises or lowers the roller j, which acting through arm j', link j⁴ and arm j⁵, effects an oscillation of shaft h^6 115 which, as previously stated, is so connected as to effect the upward and downward movements of the cast-off bar.

I will now describe my preferred relative and absolute timing of the cams d^4 and J 120 which respectively actuate the needle bar and the cast-off bar carrying the needle and the cast-off respectively. The diagram, Fig. 9, indicates the timing of the movements referred to, the full line d representing the 125 timing of the needle movements and the broken line h representing the timing of the cast-off. From the upper to the lower end of the diagram a complete cycle of movements is represented extending from the 130

commencement of operation for a given button until the complete attachment of that button to the work. From the upper to the lower end of the diagram it is divided into twenty portions representing equal intervals or units of time, the entire distance from zero to 20 representing a complete revolution of the main shaft Z. This diagram will enable one skilled in the art to easily 10 construct the cams d⁴ and J in accordance with my invention.

On analysis the diagram Fig. 9 shows the following operations to take place with respect to the needle and cast-off. The zero 15 and 20 position is the initial position of the machine while it is prepared to start upon the operation of attaching a button, and this position is that which is illustrated in Figs. 1 and 2 of the drawings, the cast-off 20 being at its highest point and the needle being at a point slightly lower than its highest point. From zero to 2 the line d passes from the right to the left, this indicating a descent of the needle, and this portion of 25 the line will be seen to be curved so as to give the most advantageous needle descent. The needle will enter the work between the points 1 and 2, and it will be seen that before entering the work the needle's descent is 30 rapid, thus economizing in time, while during penetration of the work the needle's movement is less rapid and therefore of greater penetrating force. This operation takes care of the natural slowing of the 35 needle on meeting the resistance of the work, and at the same time the entire motion is a smooth one and calculated without need of considering other conditions. During the same period of time from zero to 2, the cast-off 40 is seen to make an easy descent to the position that it is to have upon the elevation of the needle. From 2 to 3 the needle and cast-off are stationary, this being the period when the looper is passing a thread 45 into the needle's hook. Thereupon from lines 3 to 5 the needle makes its complete ascent from lowest to highest position. During this ascent the needle bar does not require to operate upon lugs on the cast-off 50 bar, since the latter is independently taken care of as explained. The cast-off when it is in protecting position upon the needle's hook is slightly higher than the needle's point and consequently when the needle has nearly 55 reached the height of the cast-off as indicated at point 4, the cast-off must begin to rise, and its cam effects its elevation as shown, without shock or noise. From point 4 to 5 the needle and cast-off are rising at 60 substantially the same speed, and at point 5 they both reach substantially their highest positions. At this stage it will be understood that a loop of thread has been pulled up through the work and through the eye of 65 a button, said loop being then held in ele-

vated position by the needle's hook, protected by the cast-off. From 5 to 6 the needle and cast-off are stationary and during this time the work and button are shifted slightly from the operator so that on the next descent the needle will pass outside of the button's eye for making the second puncture. Thereupon the needle again makes a complete descent from point 6 to point 7 $\frac{1}{2}$, similar to its previous descent, and again 70 puncturing the work. The needle reaches its lowest position and remains there until point 8 $\frac{1}{2}$ of the diagram is reached, while another loop of thread is being applied to it. During this period from point 6 to point 8 $\frac{1}{2}$ or 9, 80 the cast-off is also caused to descend, but its manner of descent is not restricted by that of the needle, and the two curves of descent will be seen to be substantially different. The cast-off's descent is one commencing 85 easily and ending up with an easy and gradual motion so that when the cast-off comes into contact with the work no blow is struck, it on the contrary gradually and smoothly entering its position within the 90 puncture in the work. This stage of the operations is illustrated by Fig. 3, in which the needle is about to take a loop and the cast-off is in contact with the work protecting the first loop from again engaging the 95 needle's hook. It will be noticed that thereupon the needle commences to rise in advance of the cast-off, and it will rise until the hook is covered by the cast-off at point 9 of the diagram, the two thereafter rising 100 in practical unison until substantially the highest position of each has again been attained at point 10 $\frac{1}{2}$ of the diagram. From this point to point 12 of the diagram there is no movement of the needle and cast-off. 105 Fig. 4 shows the position occupied by them during this idle period. During this time the spreader G has begun to come into action to enter the loop held conjointly by the needle and cast-off. 110

From and after the point 12 illustrated in Fig. 4, the cast-off has no function, nor is it compelled to partake of the needle's movements, and a straight dotted line is therefore shown on the diagram from point 115 12 to 20. The needle on the contrary is required to dip slightly, as indicated from point 12 to 13 for the purpose of releasing the loop which the spreader has entered, so that the spreader may then take charge of 120 the loop and pass it over the button. Immediately after this dip or descent of the needle, it rises again from point 13 to 14 to substantially its highest position and remains there while the knot is being tightened 125 and the work fed forward to the position for attaching another button. As a slight economy in time, the descent of the needle for the succeeding button may be caused to commence at point 18 of the dia- 130

gram so that when point 20, which is the same as point zero, has been again reached, the needle will be already on its way down to enter the eye of the button.

5 From the above description it will now be clearly understood how the movements of the needle and cast-off are independently calculated and effected, and from the diagram lines *d* and *h* it will be seen that the 10 most advantageous, economical, easy and silent mode of operation of both of the parts is secured without conflict and in entire and perfect harmony with each other.

It should be said that the type of knot 15 shown in the specific embodiment of the drawings hereof, is a well known one. A series of knots are formed, each attaching its button, and each formed from a continuous thread which is not required to be severed between knots. The first loop is carried 20 through the work and then through the button's eye, and held there temporarily while a second loop is pulled through the work and through the first loop. In pulling up the 25 second loop it is customary to pull it so far as to cause a tightening or taking up of the first loop. The second loop is spread and placed over the head of the button. The thread mechanism then takes up the thread 30 supply for tightening the second loop and thereby tightening the knot.

While the spreader *G* may be of any desired form, the following is my preferred form. Fig. 1 shows it in front view, Fig. 35 2 left end view, and Fig. 8 enlarged top view. The spreader is carried at the foot of a vertical axis or bar *G'* which may be termed a spreader bar, this bar being capable of sufficient oscillation to swing the 40 spreader into and out of spreading position. As seen in Fig. 8 the spreader is not mounted directly on the bar *G'*, but upon a short axle contained in a horizontal sleeve *g*, so that the spreader point *g'* can be tipped over at 45 the proper time for shedding the thread loop. A clamp sleeve *g*² serves to hold the spreader in place and also serves for the attachment of a spring *g*³, whose tendency is to hold the spreader in horizontal position 50 against tipping. The spreader point *g'* is at such a distance from the spreader bar *G* that when the latter is swung the former will pass directly between the two strands of thread extending downwardly from the elevated needle, as clearly seen in Fig. 4.

For effecting the swinging of the spreader and spreader bar, the following actuating mechanism may be employed. Secured at the upper end of the bar *G'* is a lever *g'* 60 extending toward the rear, as seen in the top view Fig. 10, said lever having at its outer end a roller *g*⁵ which engages in the forked end of a lever *g*⁶ centrally pivoted at *g*⁷. The lever *g*⁶ at its other end is pivoted at *g*⁸ to a longitudinally reciprocating

rod *g*¹¹. The pivot *g*⁷ of the lever *g*⁶ is supported on a stationary bracket *g*⁹ formed on or secured to the head *A*² of the machine, said bracket having the pivot *g*⁷ at its rear end at the left-hand of Fig. 2, and formed 70 at the other end to afford a bearing for supporting the upper end of the spreader bar *G*'. It is intended that the double lever *g*⁶ shall be oscillated by the reciprocating rod *g*¹¹ for the purpose of oscillating the 75 spreader bar. To actuate the parts the said rod *g*¹¹ is connected at its right-hand end, Fig. 10, to a swinging arm *g*¹², said arm *g*¹² being shown also in dotted lines Fig. 2, it having at its forward end a pivot *g*¹⁵ to 80 permit its swinging. From the under side of lever *g*¹² depends a pin and roller *g*¹³, Figs. 2 and 10, which engages in the groove of cam *g*¹⁴ fixed to and rotating with the main shaft *Z*. The contour of the cam *g*¹⁴ 85 is so timed as to cause the inward and outward swinging movements of the spreader at the times and in a manner that will be understood from the preceding description 90 of the machine's operation.

When the spreader has been swung entirely inward carrying the second loop with it to a point beyond that shown in Fig. 4, the spreader is then required to tip downwardly and shed the loop over the head of 95 the button. For effecting this tipping movement, a finger or projection *K* is provided on the spreader, it being more clearly shown in Fig. 8. When the spreader has been swung completely inward, the finger *K* 100 comes beneath the end *k* of a swinging arm *k*', pivoted at *k*² to a fixed lug *k*³. At the other end of arm *k*' is a pivotal connection *k*⁴ to an upwardly extending link *k*⁵, see Fig. 2, the upper end of said link being pivotally connected to an arm *k*⁶, secured to an auxiliary shaft *k*⁷, Figs. 1 and 10. The shaft *k*⁷ extends from left to right and at its right end passes through journal *k*⁸ to where at its extremity it has secured to it an arm *k*⁹ 110 extending downwardly and to the rear, where it carries a roller *k*¹⁰, Figs. 2 and 10. Said roller *k*¹⁰ engages with a cam *k*¹¹ mounted on the shaft *Z*. The roller merely bears upon the cam which is generally circular but has an eccentric or projecting portion *k*¹². When the portion *k*¹² comes into 115 position beneath the roller *k*¹⁰, it lifts and then drops the roller so as to cause the tipping and then the restoration of the spreader 120 as described. In order to hold the roller *k*¹⁰ in contact with its operating cam a spring *k*¹³, Fig. 2, may be employed, it being shown secured at one end to the arm *k*⁹ carrying the roller, and at its other end to a fixed part 125 of the machine frame.

I will now describe a supporter or means for supporting or backing up the needle against deflection when the same is put under strain through tension on the thread. 130

Such backing up of the needle may be necessary from various causes, such for example as the pull on the thread at the time the work is fed or during the operation of the spreader. Although the needle is stout and incapable of bending excessively under the pull of the thread, yet it has been found that when successive jerks are imposed upon the needle at the very rapid rate that is required in a machine of this kind, the needle will before long become permanently affected. It will take a slight set or curve away from its proper position, and this will so far interfere with the other mechanisms and the proper operation of the machine, as sometimes to cause breakage or at least the need of stoppage for the purpose of repair or replacement of the needle. In my preferred arrangement the needle supporter hereof is one which is movable relatively to the needle, and in fact moves from the needle to idle position and back again to the needle for affording it support; and the means for operating the supporter is automatic and, when the supporter is to prevent damage to the needle from the spreader's action, then I prefer to actuate the supporter from the movement of the spreader. The following is a convenient mechanism for carrying out this part of my improvements. A needle supporter M is illustrated in the drawings and as shown it consists of a device which is independent of the mechanism for reciprocating the needle. The supporter M is shown as a movable device capable of being shifted from its idle position shown in Fig. 3 to its needle supporting position shown in Fig. 4. To adapt it for this the supporter is pivoted at m to the overhanging arm A² of the machine so as to enable it to swing rearwardly to idle position and forwardly into contact with the needle near the point of the latter while the needle is in raised position. To an extension m' is secured a spring m², which being under tension tends to swing the supporter around the pivot m so as to normally hold the supporter in its rearward position shown in Fig. 3. It will be understood that the supporter M is sufficiently curved toward the right, Fig. 1, to bring its supporting extremity in registry with the needle. For causing the actuation of the supporter, it may be provided with a projection or lug m³ adapted to be contacted by an actuating device.

It has already been explained that Figs. 3 and 4 show two successive positions of the machine's operation. In Fig. 3 the needle is about to move vertically upward for forming the second loop. In Fig. 4 the needle is in upward position and the point g' of the spreader is entering the loop for the purpose of spreading it preparatory to shedding it over the button. In Fig. 3 the needle supporter M is in idle position. In Fig. 4, how-

ever, it is shown as having come into needle supporting position so as to firmly back up the needle during the operation of the spreader. From this figure the utility of the device will be plainly seen. The button is slightly to the rear of the needle so that the loop stands at an incline. The spreader in entering the loop puts the thread under heavy tension, thus causing a side strain on the needle, and moreover the spreader's movement is one toward the rear, thus increasing the strain and the tendency to deflect the needle rearwardly. Such deflection, however, is entirely prevented by the additional strength and support given to the needle by the supporter M.

Since in the present embodiment of the invention the needle supporter is for coöperation with the spreader by resisting an objectionable tendency of the latter, I prefer to operate the supporter from the same mechanism which operates the spreader and even from the spreader bar G' itself. For this purpose a cam m⁴ may be clamped directly on the oscillating spreader bar, as clearly seen in top view Figs. 5 and 6, this cam being located to coöperate with the projection m³ on the supporter and having such contour as to cause the swinging of the supporter at the proper times. The position of cam m⁴ in Fig. 5 corresponds to the supporter's position in Fig. 3, the supporter then being rearward so as to enable the needle bar to clear it in its up and down movements. When, however, the spreader comes into operation and swings inwardly, the spreader bar carries the cam m⁴ around to the position shown in Fig. 6, which causes the swinging of the supporter and brings the latter immediately behind the needle as shown in Figs. 4 and 6. Therefore while the spreader is acting, the needle is efficiently backed up or supported against possible deflection or injury.

The operation of the present machine need not be further set forth as it has been quite fully described above, especially in connection with the diagram Fig. 9, where the relation of the needle movements to the cast-off movements was fully shown and explanations made in connection therewith, indicating the time of operation of the spreader, looper, etc.

It will be seen that by reason of the construction above shown and described a button machine is provided which answers the objects and affords the advantages of the invention as hereinbefore set forth; and other advantages will be apparent to those skilled in the art.

It is to be understood that the present invention in its broader aspects is not limited to the precise construction shown nor to any particular construction by which the invention has been or may be carried into effect,

since many changes may be made in the details of the parts without departing from the main principles of the invention and without sacrificing its chief advantages.

5. While termed a button attaching or sewing machine, it will be understood that the present invention in its principles might be employed with articles other than buttons but analogous thereto, and the description 10 and claims hereof are to be construed accordingly.

Having thus described my invention, what I claim and desire to secure by Letters Patent, is:

15. 1. A button attaching machine of the type in which two successive loops are drawn through the work and formed into a knot for the attachment of each button, comprising in combination a work support, a hooked needle fitted to move downwardly and upwardly, a cast-off located in co-operative engagement with said needle and fitted to move downwardly and upwardly, a common driving part, needle mechanism actuated from said part adapted for causing the needle to descend rapidly to the work and thence through the work and return in the formation of each of said two successive loops, and means for causing the cast-off in its descent during the second descent of the needle to retard relatively to the needle so as to come to the work with an easy approach and contact.

20. 2. A button attaching machine comprising in combination loop forming mechanism, a spreader, a spreader shaft or pivot permitting the spreader to tip, a spreader bar carrying said shaft and spreader and adapted to swing the spreader into a loop, a spreader tipper adapted to shift and located to cause the spreader's tipping when shifted, and means independent of said spreader shaft and bar for shifting said tipper for causing the spreader to shed its loop.

25. 3. A button attaching machine comprising in combination loop forming mechanism, a spreader, a spreader shaft or pivot permitting the spreader to tip, a spreader bar carrying said shaft and spreader and adapted to swing the spreader into a loop, a finger or projection carried by the spreader, a spreader tipper adapted to shift and located to contact said finger to cause the spreader's tipping when shifted, and means independent of said spreader shaft and bar for shifting said tipper for causing the spreader to shed its loop.

30. 4. A button attaching machine comprising in combination, a reciprocating sewing needle, a loop spreader, means for operating said spreader to spread a loop engaged on said needle, a movable needle supporter, and connections whereby the spreader's movement effects a shifting of said supporter to and from the needle, whereby the needle

is supported against deflection while the spreader is imposing a strain thereon.

35. 5. A button attaching machine comprising in combination a work support, a needle carrier reciprocable in a straight line, a straight needle thereon adapted to take the thread near its point, means to actuate the carrier to cause the needle to penetrate the work from above and return, and an intermittent needle backer adapted to contact the needle substantially above the work while the needle is disengaged from the work, and means independent of the needle and carrier for causing the backer to laterally approach and recede from the needle.

40. 6. A button attaching machine comprising in combination a work support, a needle carrier reciprocable in a straight line, a straight hook needle thereon adapted to take the thread near its point, a cast-off co-operating with said needle, means to actuate the carrier to cause the needle to penetrate the work from above and return, and an intermittent needle backer adapted to contact the needle substantially above the work while the needle is disengaged from the work.

45. 7. A button attaching machine comprising in combination a work support, a needle carrier reciprocable in a straight line, a straight hook needle thereon adapted to take the thread near its point, a cast-off co-operating with said needle, means to actuate the carrier to cause the needle to penetrate the work from above and return, and an intermittent needle backer adapted to contact the needle substantially above the work while the needle is disengaged from the work, a spreader for engaging a loop while on the needle for spreading it over a button, and means independent of the needle and carrier for causing the backer to laterally approach the needle to back it up when the spreader is in action.

50. 8. A button attaching machine comprising in combination a work support, a needle carrier, a needle thereon adapted to take the thread near its point, means to actuate the carrier to cause the needle to penetrate the work twice for each button to form two button attaching loops, a spreader adapted to enter one of said loops while engaged on the needle for spreading it over the button head, and a needle backer for opposing the spreader's tendency to flex the needle, and means for moving said backer into and out of contact with the needle.

55. 9. A button attaching machine comprising in combination a work support, a needle carrier reciprocable toward and from said support, a needle on said carrier adapted to take a thread near its point, a loop spreader adapted to enter a thread loop engaged on said needle while the needle is out of the work, means for operating said spreader to

- spread open such loop and place it over the head of a button being attached, a needle backer shiftable relatively to and from the needle's path and constructed to back up 5 the needle during the operation of and in opposition to said spreader, and means for intermittently moving said backer to the needle.
10. A button attaching machine comprising in combination, a work support, a needle carrier reciprocable toward and from said support, a needle on said carrier adapted to take a thread near its point, mechanism including a moving loop-spreader in said 15 machine adapted to cause a pull upon the thread engaging said needle, in a direction tending to laterally deflect the needle from its path while out of the work, a needle backer shiftable relatively to and from the 20 needle's path and constructed to back up the needle while out of the work against the laterally deflecting tendency aforesaid, and means for intermittently positively moving said backer into engaging contact with the 25 needle.
11. A button attaching machine comprising in combination, a work support, a needle carrier reciprocable toward and from said support, a needle on said carrier adapted 30 to take a thread near its point, mechanism for feeding the work in said machine adapted to cause a pull upon the thread engaging said needle in a direction tending to laterally deflect the needle from its path while out 35 of the work, a loop-spreader movable in the direction of work-feed for engaging and spreading a loop while on said needle, a needle backer shiftable relatively to and from the needle's path and constructed to 40 back up the needle while out of the work against the laterally deflecting tendency aforesaid, and means for intermittently positively moving said backer into engaging contact with the needle.
- 45 12. A button attaching machine comprising in combination, a work support, a needle carrier reciprocable toward and from said support, a needle on said carrier adapted to take a thread near its point, a loop spreader 50 adapted to cause a pull upon the thread en-
- gaging said needle in a direction tending to laterally deflect the needle from its path while out of the work, a needle backer shiftable relatively to and from the needle's path and constructed to back up the needle while 55 out of the work against the laterally deflecting tendency aforesaid, and means other than the needle and carrier for intermittently moving said backer first to needle engaging position and then from such position. 60
13. A button attaching machine comprising in combination, a work support, a needle carrier reciprocable toward and from said support, a hooked straight needle on said carrier adapted to take a thread near its point, a loop spreader adapted to cause a pull upon the thread engaging said needle in a direction tending to laterally deflect the needle from its path while out of the work, a needle backer shiftable relatively to and 65 from the needle's path and constructed to back up the needle while out of the work against the laterally deflecting tendency aforesaid, and means for intermittently positively advancing said backer into contact against said needle and holding it there while the needle is substantially passive. 75
14. In combination, a work support, a needle carrier reciprocable in a straight line toward and from said support, a straight 80 needle on said carrier adapted to take its thread near its point, a device operating to enter a loop of the thread engaged on said needle to intermittently impose a lateral deflecting strain upon the needle while out of the work, a needle backer shiftable relatively 85 toward and from the needle's path and adapted to contact the needle in opposition to such strain, and automatic mechanism for intermittently positively advancing said 90 backer toward the needle path and into strain-resisting contact with the needle, and holding it there until such strain is removed.

In testimony whereof I affix my signature in presence of two witnesses.

JOHN KIEWICZ.
